UNITED STATES PATENT OFFICE.

AMOS B. TAYLOR, OF WOLLASTON, MASSACHUSETTS.

LOOM-SHUTTLE.

SPECIFICATION forming part of Letters Patent No. 373,913, dated November 29, 1887.

Application filed June 24, 1886. Serial No. 206,173. (No model.)

To all whom it may concern:

Be it known that I, AMOS B. TAYLOR, a citizen of the United States, residing at Wollaston, in the county of Norfolk and State of Massachusetts, have invented certain Improvements in Loom-Shuttles, of which the following is a full, clear, and exact description, reference being had to the accompanying drawings, making part of this specification, in

10 which—

Figure 1 is a central vertical section through a portion of a shuttle constructed in accordance with my invention. Fig. 2 is a horizontal section through the same on the line *x x* of Fig. 1, with the cop in place upon the expanded spindle. Fig. 3 is a central vertical section of a portion of the shuttle with the spindle raised. Fig. 4 is a perspective view of the inner end of the spindle detached and 20 the friction-roll used in connection therewith.

My invention relates to that class of loom-shuttles in which a split spindle is employed, within which is placed a longitudinal sliding wedge or pin which acts near the point of the spindle to expand the same when closed down into the shuttle for the purpose of holding the cop firmly in place; and my invention consists in a novel and effective construction of the devices for operating the said sliding wedge or pin, as hereinafter more fully described, 25 and specifically pointed out in the claim.

In the said drawings, A represents the shuttle-body of the usual form, within a cavity or recess, *a*, at one end of which is pivoted at *b* the spindle B, over the heel or base *c* of which is placed the ordinary flat heel-spring, *d*, which holds the spindle in place when raised or when closed down in a horizontal position within the cop-chamber *e* of the shuttle. At the upper front corner or portion of the heel *c* of the spindle is formed a semicircular or arc-shaped notch or recess, *f*, which extends entirely across the width of the heel *c*, and forms a bearing or support for an anti-friction roll, *g*, 40 upon the upper side of which bears the heel-spring *d*, the roll *g* being thus interposed between the heel of the spindle and the spring, and being held securely in place by the latter, the roll having no gudgeons or supporting-shaft, but merely resting in the curved notch or recess *f*. It will be obvious that the roll *g*

will thus cause the friction and wear to be reduced to a minimum, and that even if no lubricant is used the wear will be slight compared with that which occurs where the spring 55 is in direct contact with the heel of the spindle, as heretofore, and consequently the durability of the parts is greatly increased and the cost of repairs reduced, while the liability of the failure of the spring to properly close down 60 the spindle into its horizontal position is entirely avoided, and any possibility of damage to the warp from this cause effectually prevented. The spindle B is split lengthwise from near the point entirely through the heel, 65 or, if preferred, only as far as the heel, its two parts, *h i*, being grooved longitudinally, as seen at *k*, for the reception of a long wedge or pin, *m*, the point of which, when pushed forward in a manner to be presently explained, is 70 brought into contact with the inclines or ends *n* of the grooves *k*, and thus separates the two parts *h i* and expands the spindle near its point or front end against the hollow interior of the cop D, which is thereby held securely 75 in place, as desired.

A wedge or expander-pin placed within a split spindle and acting near the point of the same in the manner described has long been in use and forms no part of my invention, which 80 merely relates to the means employed for operating the said expanding-pin, as will now be described. Within a central slit in the under side of the shuttle-body A, beneath and slightly in the rear of the pivot *b* of the spindle B, is 85 pivoted on a pin, *p*, in line with the axis of the spindle, a curved plate or rocker-arm, *G*, of the form seen in Figs. 1 and 3, which extends around in front of the heel *c* and upward into an enlarged or recessed portion, *q*, of the 90 split between the two portions *h i*, and thence into and through a notch or open slot, *r*, at the rear or inner end of the expander-pin *m*, above which it is provided with a lip or other suitable projection or enlargement, *s*, as seen in 95 Figs. 1 and 3, which prevents the end of the arm *G* from dropping down out of the notch *r* of the pin *m* as the spindle is raised on its pivot out of the shuttle. Beneath the expander-pin *m* the end of the arm *G* is provided with a stop 100 or shoulder, *t*, which bears against the under side of the pin and prevents the end of the arm

G from sliding up through the notch *r* as the spindle is closed down into the shuttle. The pivots *b p* of the spindle and rocker-arm are so placed with respect to each other that the said spindle and arm will rock in arcs of circles eccentric to each other, and thus when the spindle is raised the upper portion of the arm G will be carried backward toward the heel *c*, as seen in Fig. 3, drawing with it the expander-pin *m*, which thus allows the two portions *h i* of the spindle to come close together to allow of the cop D being easily slipped thereon or the cop-tube to be removed therefrom. When the spindle is closed down into the shuttle, the arm G is rocked downward on its pivot by the contact of the expander-pin *m* with the shoulder *t*, and as the arm descends in the arc of a circle its upper portion is carried forward toward the point of the spindle, thus pushing the pin *m* forward within the spindle and causing its point to act upon the inclines *n*, thus expanding the spindle near its point or front end against the hollow interior of the cop D, which is thereby held securely in place, as desired.

It will be observed on an inspection of Fig. 3 that as the spindle commences to be depressed the pin *m* has no forward movement until its under side is brought into contact with the shoulder *t* of the arm G. The operation of pushing forward the pin *m* to expand the spindle then commences, which requires the exertion of considerable force, and this movement is effected by the arm G without any sliding or rubbing movement whatever against the pin, but merely by an end-thrust, and consequently there is hardly any appreciable wear, even when the parts are not oiled. It will be seen that the curved arm or plate G does not come into contact with the spindle itself at any point, as the recessed portion *q* is of sufficient width to prevent its contact with either of the parts *h i*, and consequently the plate G does not act as or perform any of the functions of a wedge, or operate in any way to expand the spindle, except through the intervention of the pin *m* which it actuates.

Although the anti-friction roll *g* may be used to great advantage in connection with a common spindle having no expanding device, as it causes the spring to act with more force to close down the spindle, it will be found particularly adapted for use with that class of shuttles having split spindles provided with expanding devices, for the reason that with the latter, additional power is required to force down the spindle on account of the increased resistance offered, and consequently where my friction-roll is employed, a spring of the usual power will readily overcome the resistance offered by the expanding device, whereas, if no friction-roll is used, and a more powerful spring is employed to overcome the extra resistance produced by the employment of an expanding device, the friction would be materially increased, and the parts would soon become worn and require to be renewed or repaired.

What I claim as my invention, and desire to secure by Letters Patent, is—
The combination, with a shuttle-body and a split spindle pivoted therein, having a longitudinally-sliding wedge or pin, *m*, adapted to expand said spindle near the point, of a rocking pivoted plate or arm, G, extending around in front of the heel of the spindle, and upward through a notch or slot, *r*, in the expander pin or wedge *m*, and having a lip or projection, *s*, on that portion which extends above the slot *r*, and a stop or shoulder, *t*, on that portion immediately beneath the slot *r*, whereby the upper end of the arm G is prevented from dropping down out of the said slot or sliding up through the same as the spindle is raised or depressed, substantially as described.

Witness my hand this 22d day of June, A. D. 1886.

AMOS B. TAYLOR.

In presence of—

P. E. TESCHEMACHER,
W. J. CAMBRIDGE.
